Horatio E. Bellows
ATTORNEY

UNITED STATES PATENT OFFICE.

MAURICE ANDERSON, OF CRANSTON, RHODE ISLAND, ASSIGNOR TO V. E. BLACK COMPANY, A CORPORATION OF RHODE ISLAND.

GARMENT-FASTENER.

1,386,592.

Specification of Letters Patent.

Patented Aug. 9, 1921.

Application filed February 26, 1921. Serial No. 448,006.

To all whom it may concern:

Be it known that I, MAURICE ANDERSON, a citizen of the United States, residing at Cranston, in the county of Providence and State of Rhode Island, have invented certain new and useful Improvements in Garment-Fasteners, of which the following is a specification.

My invention relates to garment fasteners commonly known as pins or clasps.

The essential objects of my invention are to insure a secure and continuous engagement of the tongue with the catch or retaining member; to facilitate the removal of the fastener from the garment; and to attain these ends in an inexpensive and solderless structure.

To the above ends essentially my invention consists of such parts and combinations of parts as fall within the scope of the appended claim.

In the accompanying drawings which form a part of this specification—

Figure 1 is a rear elevation of the body blank before finally bending the ends,

Fig. 2, a plan of the body member after final bending;

Fig. 3, a side elevation of the complete fastener in disengaged position,

Fig. 4, a bottom plan view of the same in closed position,

Fig. 5, a fragmentary section on line 5—5 of Fig. 4, and

Fig. 6, a perspective view of a modified form of my invention.

Like reference characters indicate like parts throughout the views.

In its present and preferred form of embodiment, the body of my fastener is cut and bent initially by suitable dies from a thin resilient metallic sheet. The portion 10 is oblong and provided near one end with a longitudinally disposed oblong opening 11 intermediate this opening and the adjacent end of the strip the latter is slightly transversely curved, and a shoulder 13 is raised

in the material extending from the opening to the end of the strip. The corners of the opposite end of the strip 10 are preferably downwardly depressed or inclined as at 14 forming a resultant cavity 15 therebetween.

The end of the strip containing the opening is rolled inwardly upon itself to form a sleeve 17 with an arcuate slot or opening 11, disposed centrally and transversely of the sleeve in its upper portion, with the bearing shoulder 13 adjacent and immediately below the slot, all as shown in Fig. 2. The opposite end of the strip 10 is inwardly bent in the form of a loop or catch 18. In the sleeve 17 is a pintle or pivot member 20. A tongue 21 has a loop 22 upon its end embracing the pivot member 20. The tongue in this instance is slightly curved upwardly. Near its rear end the tongue rests upon the shoulder 13. In closing the fastener the outer end of the tongue is depressed and brought laterally beneath the catch 18 and into the seat 15. In this instance the body 10 is curved.

In another form of my fastener, as shown in Fig. 6, the tongue 23 is broad, and has instead of a pointed end, a curved resilient lip 24 adapted to clasp or overlap a loop 25 on the base 10.

I claim:—

A garment fastener comprising an oblong body having near one end a longitudinally disposed opening with a transverse curved portion between the said opening and the adjacent end of the body with a shoulder raised in the material extending from said opening to the end of the body, and said end formed into a sleeve with a portion of said opening disposed in said sleeve, a pintle in said sleeve, and a tongue mounted on said pintle and resting near its pivot end on said shoulder.

In testimony whereof I have affixed my signature.

MAURICE ANDERSON.
